UNITED STATES PATENT OFFICE

114,459

DESIGN FOR A SHOE

Frederick W. Ochs, Boston, Mass., assignor to
United Shoe Machinery Corporation, Paterson, N. J., a corporation of New Jersey

Application January 19, 1939, Serial No. 82,447

Term of patent 3½ years

To all whom it may concern:

Be it known that I, Frederick W. Ochs, a citizen of the United States, residing at Boston, in the county of Suffolk and Commonwealth of Massachusetts, have invented a new, original, and ornamental Design for Shoes, of which the following is a specification, reference being had to the accompanying drawing, forming a part thereof.

In the drawing,

Fig. 1 is a top plan view of a shoe showing my new design; and

Fig. 2 is a view in side elevation of the shoe.

The dominant feature of my design is in the arrangement wherein portions of the upper at opposite sides of the ball and waist of the shoe are of interlaced strip formation comprising strips which extend diagonally upward from the tread sole at substantial angles to the perpendicular in directions lengthwise of the sole edge, and

wherein the rest of the upper, including the toe and heel portions and a connecting portion extending from said toe portion to the throat opening of the shoe and rearwardly along opposite sides of said opening to said heel portion, is of full upper formation presenting no interlaced strip effect, the upper boundaries of said interlaced strip portions being defined by zigzag lines presenting the appearance of V-shaped scallops, and the heelward end of the interlaced strip portion at one side of the shoe having a general outline presenting the appearance of a wedge the point of which is directed rearwardly and is located above the heel of the shoe.

I claim:

The ornamental design for a shoe, as shown and described.

FREDERICK W. OCHS.
